UNITED STATES PATENT OFFICE.

THOMAS J. MALONEY, OF ST. LOUIS, MISSOURI.

DESIGN FOR A CHANDELIER.

Application filed July 10, 1922. Serial No. 3,029. Term of patent 3½ years.

To all whom it may concern:

Be it known that I, THOMAS J. MALONEY, a citizen of the United States, residing in the city of St. Louis, State of Missouri, have invented a new, original, and ornamental Design for a Chandelier, of which the following is a specification, reference being had to the accompanying drawing, forming part thereof.

The figure is a side elevational view of a chandelier showing my new design.

I claim:

The ornamental design for a chandelier as shown.

THOMAS J. MALONEY.
